UNITED STATES PATENT OFFICE.

ORRIN B. READ, OF CHARLOTTE, VERMONT.

DESIGN FOR A CURRYCOMB AND CARD.

SPECIFICATION forming part of Design No. 26,334, dated November 24, 1896.

Application filed October 12, 1896. Serial No. 608,651. Term of patent 14 years.

To all whom it may concern:

Be it known that I, ORRIN B. READ, a citizen of the United States, residing at Charlotte, in the county of Chittenden and State of Vermont, have invented and produced a certain new and original Design for a Combined Currycomb and Card; and I do declare the following to be a full, clear, and exact description of the invention, such as will enable others skilled in the art to which it appertains to make and use the same.

My invention has relation to a design for a combined currycomb and card.

It relates to the entire configuration of the comb and card.

My invention relates particularly to a combined comb and card, as illustrated in the accompanying drawings, in which—

Figure 1 is a perspective view of a combined currycomb and card embodying my design, and Fig. 2 is a longitudinal section of the same.

The leading features of my design appear in the following description:

1 represents the handle, 2 the shank, and 3 the tri-armed spider, secured to the base 4. This base is formed with integral converging wings 5 and 6, their contiguous outer edges being secured together, as shown in the drawings, and at each side of the said edges is a knob or button 7. One wing 5 is provided with a series of parallel serrated blades 8 and the opposite wing with a series of flexible carding-teeth 9.

10 represents a swivel-ring secured in one end of the handle.

Having thus fully described my invention, what I claim as new, and desire to secure by Letters Patent of the United States, is—

The design for a combined currycomb and card, substantially as herein shown and described.

In testimony whereof I hereunto affix my signature in presence of two witnesses.

ORRIN B. READ.
